(57) **CLAIM**

The ornamental design for a drop-in, threaded body mounting for an industrial grade thumb control joystick, as shown and described.

DESCRIPTION

FIG. 1 is a perspective, front view of the drop-in, threaded body mounting for an industrial grade thumb control joystick; FIG. 2 is a perspective, rear view of the drop-in, threaded body mounting for an industrial grade thumb control joystick; FIG. 3 is a top view of the drop-in, threaded body mounting for an industrial grade thumb control joystick; FIG. 4 is a front view of the drop-in, threaded body mounting for an industrial grade thumb control joystick; FIG. 5 is a cross section through a centerline of the front view of the drop-in, threaded body mounting for an industrial grade thumb control joystick; FIG. 6 is a back view of the drop-in, threaded body mounting for an industrial grade thumb control joystick; FIG. 7 is a bottom view of the drop-in, threaded body mounting for an industrial grade thumb control joystick; FIG. 8 is a side view of the drop-in, threaded body mounting for an industrial grade thumb control joystick, the opposite side being a mirror image thereof; FIG. 9 is a perspective, front view of the drop-in, threaded body mounting for an industrial grade thumb control joystick illustrated as part of an industrial grade inductive thumb control joystick assembly having a plastic actuator top; FIG. 10 is a perspective, rear view of the drop-in, threaded body mounting for an industrial grade thumb control joystick illustrated as part of the industrial grade inductive thumb control joystick assembly having a plastic actuator top; FIG. 11 is a front view of the drop-in, threaded body mounting for an industrial grade thumb control joystick illustrated as part of the industrial grade inductive thumb control joystick assembly having a plastic actuator top; FIG. 12 is a back view of the drop-in, threaded body mounting for an industrial grade thumb control joystick illustrated as part of the industrial grade inductive thumb control joystick assembly having a plastic actuator top; FIG. 13 is a bottom view of the drop-in, threaded body mounting for an industrial grade thumb control joystick illustrated as part of the industrial grade inductive thumb control joystick assembly having a plastic actuator top; FIG. 14 is a side view of the drop-in, threaded body mounting for an industrial grade thumb control joystick illustrated as part of the industrial grade inductive thumb control joystick

assembly having a plastic actuator top, the opposite side being a mirror image of thereof;

FIG. 15 is a side view of the drop-in, threaded body mounting for an industrial grade thumb control joystick illustrated as part of the industrial grade inductive thumb control joystick assembly having a plastic actuator top including a mock panel and mounting hardware;

FIG. 16 is a perspective, front view of the drop-in, threaded body mounting for an industrial grade thumb control joystick illustrated as part of an industrial grade inductive thumb control joystick assembly having a silicone rubber push button actuator top;

FIG. 17 is a perspective, rear view of the drop-in, threaded body mounting for an industrial grade thumb control joystick illustrated as part of the industrial grade inductive thumb control joystick assembly having a silicone rubber push button actuator top;

FIG. 18 is a front view of the drop-in, threaded body mounting for an industrial grade thumb control joystick illustrated

as part of the industrial grade inductive thumb control joystick assembly having a silicone rubber push button actuator top;

FIG. 19 is back view of the drop-in, threaded body mounting for an industrial grade thumb control joystick illustrated as part of the industrial grade inductive thumb control joystick assembly having a silicone rubber push button actuator top; FIG. 20 is a bottom view of the drop-in, threaded body mounting for an industrial grade thumb control joystick illustrated as part of the industrial grade inductive thumb control joystick assembly having a silicone rubber push button actuator top; and,

FIG. 21 is a side view of the drop-in, threaded body mounting for an industrial grade thumb control joystick illustrated as part of the industrial grade inductive thumb control joystick assembly having a silicone rubber push button actuator top, the opposite side being a mirror image thereof.

The broken lines represent environment and form no part of the claimed design.
